UNITED STATES PATENT OFFICE.

WALLACE S. WARNOCK, OF CHICAGO, ILLINOIS.

PRINTING PRESS.

Application filed November 6, 1920. Serial No. 422,249.

To all whom it may concern:

Be it known that I, WALLACE S. WARNOCK, a citizen of the United States, residing at Chicago, in the county of Cook and State of Illinois, have invented a new and useful Improvement in Printing Presses, of which the following is a specification.

This invention relates to delivery mechanism for printing-presses; and the primary object is to provide delivery mechanism capable of handling in a satisfactory manner the output from a press of large capacity.

A further object is to provide delivery mechanism adapted to handle the output of a press which is adapted to print either two-color work, or to print two different jobs simultaneously, if desired.

A further object is to provide delivery mechanism of this character which is adapted to handle rapidly the output of a press of large capacity in such manner as to prevent the blurring of the printed sheets.

The improved delivery mechanism is well adapted, for example, to handle the output of a press of the character set forth in Letters Patent of the United States No. 1,153,587, granted September 14, 1915, to Wallace S. Warnock. In the press described in said patent, there is employed a tympan cylinder adapted to support two sheets to be printed upon, and two printing cylinders coacting with the tympan cylinder in such manner that each cylinder may print upon both sheets of paper, as in multi-color work, or each printing cylinder may print upon alternate sheets, so that two jobs of work may be run through the press at the same time, according to desire.

In the embodiment of the invention shown in the accompanying drawings, the printed sheets of paper are taken from the tympan cylinder by a single transfer cylinder and by it delivered to a distributing cylinder which serves as a feed cylinder common to endless delivery devices, these delivery devices being adapted to receive alternate sheets from the distributing cylinder. In the printing operation, the printed sides of the sheets are exposed outwardly on the tympan cylinder. From the tympan cylinder the sheets pass about the transfer cylinder with the printed sides turned inwardly, and then about the distributing cylinder with the printed sides outwardly. From the distributing cylinder, the printed sheets

pass to the endless delivery devices, which are disposed one above the other, the sheets being received alternately by the endless delivery devices. The sheets are carried by the upper portions of the endless delivery devices with the printed sides down, are then carried back under the discharge ends of the endless delivery devices, and dropped in separate stacks, with the printed sides up. The transfer cylinder is equipped with annular serrated members which serve to hold the printed surface away from the cylinder in a manner now well understood in the art. The rollers for the front ends of the endless delivery devices are thus equipped, also, so that blurring of the sheets will not occur. When the sheets are dropped on the stacks the printed sides are up, so that the ink will have opportunity to dry.

The invention is illustrated, in its preferred embodiment, in the accompanying drawings, in which—

Figure 1 represents a broken side elevational view of a printing press equipped with the improved delivery mechanism, the printing-press itself being shown brokenly; Fig. 2, a transverse vertical sectional view taken as indicated at line 2 of Figs. 1 and 3, the view thus being directed from the rear towards the front end of the delivery mechanism; Fig. 3, a broken vertical sectional view taken as indicated at line 3 of Fig. 2, this view showing the distributing cylinder and the front end portions of the two endless delivery devices; Fig. 4, a broken plan view of the mechanism shown in Fig. 3; Fig. 5, a broken vertical transverse sectional view taken as indicated at line 5 of Fig. 1; Fig. 6, a broken longitudinal vertical sectional view taken as indicated at line 6 of Fig. 5, the view showing the gripper devices with which the endless delivery devices are equipped; Fig. 7, a broken elevational view, showing the transfer cylinder, the distributing cylinder and the associated parts; Fig. 8, a plan view of the transfer cylinder, showing cutting devices associated therewith; Fig. 9, a broken vertical sectional view taken as indicated at line 9 of Fig. 8; Fig. 10, a side view of the gear-wheel and cams which operate the cutters; Fig. 11, an edge view of the same; Fig. 12, a broken vertical sectional view taken as indicated at line 12 of Fig. 8; Fig. 13, a broken vertical sectional view taken as indicated at line 13 of Fig. 14; Fig. 110

14, a broken side elevational view showing the mechanism for actuating the shiftable cams shown in Fig. 13; Fig. 15, a broken plan view showing a portion of one of the endless delivery devices and one of the gripper devices associated therewith; Fig. 16, a broken sectional view taken as indicated at line 16 of Fig. 15; Fig. 17, a broken plan section taken as indicated at line 17 of Fig. 1 and showing the sheet-jogging mechanism employed; Fig. 18, a broken elevational view taken as indicated at line 18 of Fig. 19; Fig. 19, a broken plan view of the sheet-jogging mechanism; Fig. 20, a section taken as indicated at line 20 of Fig. 17; Fig. 21, a broken longitudinal vertical sectional view, on an enlarged scale, showing the manner in which the endless delivery devices are equipped with tapes for supporting the sheets; and Fig. 22, a broken plan view of the same.

In the embodiment illustrated, A represents the frame of the machine; B, an impression cylinder, or tympan cylinder, of a rotary press, said tympan cylinder being adapted to carry two separate sheets of paper and being equipped with two sets of grippers 1 and 1'; C, one of a pair of printing cylinders which cooperate with the tympan cylinder B; D, a transfer cylinder which receives the printed sheets from the tympan cylinder B; E, a sheet-distributing cylinder which receives the printed sheets from the transfer cylinder D; F and F', upper and lower endless delivery devices, respectively, which alternately receive the printed sheets from the distributing cylinder E; and G and G', automatically adjusted sheet-supporting platforms which receive the printed sheets from the endless delivery devices F and F', respectively.

The frame A of the machine may be of any suitable construction. It is shown as comprising a pair of suitably connected side-frames for the delivery mechanism, equipped with suitable bearings for the various cylinders and with guides for the endless chains of the endless delivery devices.

As stated, the tympan cylinder B is equipped with two sets of grippers 1 and 1', and the tympan cylinder is thus divided into two separate impression surfaces adapted to support separate sheets of paper. The printing cylinders C (one shown) are adapted to remain constantly in printing relation with respect to the tympan cylinder, or to be alternately moved into and out of printing relation, as desired. The mechanism for accomplishing this purpose is not shown in the accompanying drawings.

Referring to Fig. 12, the transfer cylinder D is equipped with grippers 2 which are adapted to engage the advance end of a sheet of paper 3 just prior to the instant when it is released by the grippers of the impression

cylinder B. It will be understood that the grippers of the impression cylinder are automatically opened at the proper instant when the transfer of the sheet from the tympan cylinder to the transfer cylinder is to occur. The means for automatically effecting release of the grippers of the tympan cylinder are not shown. The grippers 2 are carried by a rock-shaft 4 journaled in the cylinder D near its periphery and equipped with a trip-arm 4^a which is adapted to be actuated by two different cams 5 and 6 which are mounted adjustably on the frame A to enable them to be properly timed. The cam 5 serves to open the gripper 2 to enable them to receive the sheets from the tympan cylinder B; and the cam 6 serves to open said grippers to enable them to release the sheet at the instant that the grippers of the distributing cylinder E grip the sheet.

As shown in Figs. 8, 9 and 12, the transfer cylinder D preferably is equipped with sheet-cutting devices which may be employed to divide each one of the sheets in a similar manner into a plurality of sheets, or may be employed to divide alternate sheets into a plurality of sheets, the lines of cutting being different, as desired. The cutting devices comprise rock-shafts 7 and 8 having their ends suitably journaled in the side members of the frame; adjustable arms 7^a and 8^a carried by the rock-shafts and equipped, respectively, with rotary cutters 7^b and 8^b; arms 7^c and 8^c with which the rock-shafts are equipped near one end, said arms having connected therewith coil springs 9 which tend to throw the cutters to the operative position; cam-arms 7^d and 8^d with which the rock-shafts are equipped at one end; cams 7^e and 8^e adapted to alternately actuate the rock-shafts to raise the cutters from the cutting position; and a gear 10, interposed between and serving to actuate the cam-wheels, the gear 10 being actuated by a pinion 11 mounted on a shaft 12 which is equipped with a gear 13 actuated by a gear 14 mounted on the shaft of the cylinder D. The cylinder D is shown as composed of wheels or spiders mounted on a shaft, but it is to be understood that it is the same as though a continuous cylinder were employed.

It may be stated here that the cylinder D is equipped at one end with a large spur-gear 15 which is actuated by a large spur-gear 16 which rotates with the tympan cylinder B; and the spur-gear 15 meshes with and serves to actuate a large spur-gear 17 with which the distributing cylinder E is equipped. The gear 17, in turn, meshes with spur-gears 18 and 19 mounted on the shafts 18^a and 19^a, respectively, of the cylinders which support the feed ends of the endless delivery devices F and F'. Thus, the transfer cylinder, the distributing cylinder, and

the endless delivery devices are actuated from the gear 16 of the tympan cylinder B of the printing-press.

The distributing cylinder E is equipped 5 with grippers 20 mounted on a rock-shaft 20^a adapted to be actuated by a cam-arm 20^b. The grippers 20 are adapted to be opened to receive the sheets from the transfer cylinder D by means of a cam 21 which is adjustably 10 mounted on the frame A. Said grippers 20 are adapted to be opened at different points, in alternation, to deliver alternate sheets to the upper and lower endless delivery devices F and F' by means of shiftable cams 15 22 and 23, respectively, as will be understood from Figs. 3, 7, 13 and 14. These cams are preferably formed integrally with a head 24 equipped with stems 24^a which work in tubular guides 25 with which the 20 frame A is equipped. The outer ends of the stems 24^a are secured to a cross-head 24^b which is connected, by a link 26, to an arm 27 of a rock-shaft 28 which is equipped with a cam-arm 29 having a roller 29^a which 25 works in a cam-groove 30 of a cam-wheel 30^a. The wheel 30^a is actuated by a shaft 31 equipped with a bevel-gear 32 actuated by a bevel-gear 33 with which the shaft of the cylinder D is equipped.

30 It will be understood, particularly from Figs. 3 and 13, that when the head 24 is shifted outwardly the cam-roller of the arm 20^b will be engaged by the cam 23, so that the gripper 20 will be opened to release the 35 sheet at the instant it is engaged by one of the grippers of the lower endless delivery device F'; and, when the head 24 is shifted in the opposite direction, the gripper will be caused to release the sheet at the instant it is engaged by one of the grippers of the 40 other endless delivery device F. The shifting of the head 24 occurs at each revolution of the distributing cylinder E, so that the sheets are delivered alternately to the lower and upper endless delivery devices.

45 The feed end of the endless delivery device F is mounted on a cylinder 34 which is equipped at its ends with sprocket-wheels 34^a; and the discharge-end of said delivery device is mounted on a cylinder 35 which is equipped at its ends with sprocket-wheels 35^a; endless sprocket-chains 36 are mounted on said sprocket-wheels; and these sprocket-chains carry a series of gripper devices 50 which are spaced equidistant apart a sufficient distance to give room for the largest sheet which can be printed on the tympan cylinder B. The endless chains 36 are further equipped with cross-bars which carry 55 tapes adapted to support the sheets.

60 The front end of the endless delivery device F' is mounted on a cylinder 37 which is equipped at its ends with sprocket-wheels 37^a; and the rear end of said endless device F' is mounted on a cylinder 38 which is

equipped at its ends with sprocket-wheels 38^a. The sprocket-chains 39 are mounted on said sprocket-wheels. The sprocket-chains 39 are equipped at suitable intervals with gripper devices which are separated a sufficient distance to give room for the largest sheet of paper which can be printed on the impression cylinder B; and said sprocket-chains are further equipped with cross-rods or bars which support tapes upon which the sheets rest as they are carried rearwardly.

70 It will be noted from Fig. 1 that the upper endless delivery device or conveyor F has its discharge end extending a considerable distance beyond the discharge end of the lower conveyor F'; also, that the automatically adjusted platform G which receives the sheets from the upper conveyor is disposed in the rear of the platform G' which receives the sheets from the lower conveyor. These platforms are lowered automatically the thickness of a sheet of paper at the proper instant.

75 The upper portions of the chains 36 travel 80 on longitudinal guides 40, and the lower portions travel on guides 41. The upper portions of the chains 39 travel on guides 42, and the lower portions travel on guides 43. The front portions of these guides are supported on one side of the machine by a bracket 44 carried by the side frame of the machine and are supported on the other side by a bracket 45 carried by the side frame of the machine, as will be understood 85 from Fig. 2.

90 The gripper devices with which each set of conveyor-chains is equipped at suitable intervals will be understood from Figs. 2, 3, 4, 15 and 16. The chains at one side of 95 the machine carry brackets or mountings 46; and the chains at the other side carry mountings 47 which are in the form of shoes.

100 Fixedly carried by these mountings is a transverse shaft 48; and parallel with the 110 shaft 48 is a rock-shaft 49 whose ends are journaled in the mountings. The shaft 48 is equipped with a series of adjustable rings 50 carrying abutments 50^a; and the shaft 49 is equipped with a series of adjustable 115 grippers 51 which coact with the abutments 50^a to grip the sheet of paper. The shaft 48 is also equipped with an arm 52, between which and an arm 53, with which the shaft 49 is equipped, is confined a coil spring 54 120 which tends to close the grippers. A rod or pin 55 is pivotally connected with the arm 53 as shown in Fig. 16 and extends freely through a perforation in the arm 52, the spring 54 encircling the pin 55. The 125 rock-shaft 49 is further equipped with a curved actuating-arm 56 which is equipped with a cam-roller 57. The frame A is equipped with an adjustable stationary cam 58 associated with the upper conveyor F and 130

with an adjustable stationary cam 59 associated with the lower conveyor F'. These cams are adapted to depress the rollers 57 of the grippers when the sheets have been returned at the lower sides of the conveyor to the proper point to be dropped upon the stacks of sheets supported by the platforms G and G'. The cams 58 and 59 will be better understood with reference to Fig. 6. These cams are alike. The cam 58, for example has a surface 58^a adapted to engage the upper surface of the shoe 47 for the purpose of preventing the shoe from rotating about the shaft 48 at the moment when force is exerted to open the gripper device; and the member 58 also has a cam surface 58^b which is adapted to be engaged by the cam-roller 57, thus causing the arm 56 to be depressed to rotate the rock-shaft 49 and release the sheet of paper from the gripper, thus permitting the sheet to drop upon the stack where the sheets are collected.

As will be understood from Figs. 3 and 5, each of the cylinders 34, 35, 37 and 38, upon which the end portions of the endless conveyors are mounted, is provided with a segmental recess 60 which is adapted to receive and house the gripper devices of the conveyor when they pass about said cylinders. At the feed end of the conveyors, the grippers must be opened to admit the sheets delivered thereto by the distributor cylinder E. Accordingly, as will be understood from Figs. 2 and 3, the bracket 45 of the frame carries a cam-bar 61 under which the roller 57 of the gripper passes, the cam 61 serving to trip, or open, the gripper at the moment that the sheet is to be admitted. The rear end of the bar 61 has a bearing 61^a journaled on the shaft 18^a of the cylinder 34.

In a similar manner, the bracket 45 carries a trip-cam 62 associated with the lower conveyor, and which is adapted to open the gripper at the instant it is to receive the sheet of paper from the distributor cylinder E. It is desirable that the shoe 47 of the gripper shall be positively guided in passing about the cylinder at the advance end of the conveyor. Accordingly, there is provided a guide-hood 63 at the advance end of the conveyor within which the shoe 47 travels in making the circuit about the axis of the cylinder. There is also provided a guide-bar 64 associated with the conveyor, beneath which the shoe 47 travels as it approaches the cylinder at the feed end of the conveyor. The guide member 64 extends to a point near the axis of the cylinder; and to hold the shoe in its proper position as it travels about the axis of the cylinder, the cylinder is equipped with a curved or segmental shoe 65 which travels with the cylinder and which makes contact with the upper edge of the shoe, as viewed in Fig. 3. These devices

serve to maintain the shoe in proper position, as it is carried about the cylinder at the advance end of the conveyor, and serve to prevent the shoe from being twisted from its proper position during the time when the gripper device is being opened by means of the cam 61 or the cam 62, as the case may be.

The conveyor chains have mounted thereon, at suitable intervals, cross-bars or shafts 66. At suitable intervals, three of these cross-bars are grouped together, and are adapted to enter the segmental recesses 60 of the cylinders at the ends of the conveyors, thus serving to complete the circle of the cylinder. Some of these shafts are equipped at intervals with collars 67 having bearings 67^a adapted to support longitudinal tapes 68. Others of the shafts 66 are equipped with collars 69 having lugs 69^a adapted to be engaged by the looped ends of the tape in the manner shown in Fig. 21. The ends of the tape are passed through the looped portions 70 of clips 70^a which slip over the lugs 69^a. The lugs 69^a are undercut at their inner sides, so that the loops 70 will slip into the undercut portions and draw the tape under the projecting lips of the lugs 69^a. This is effected by means of screws 71 which have threaded connection with the clips 70^a, the tips of the screws bearing against the outer surfaces of the lugs, so that the loops 70 will be drawn under the lips of the lugs 69^a as the screws are turned in. It will be understood from Fig. 4 that the tapes 68 are properly spaced to support the sheet of paper as it is carried rearwardly by the endless conveyor of which the tapes form a part. While Fig. 3 shows a group of three cross-bars equipped at intervals with lugs adapted to support the tapes over the segmental recess 60, it will be understood that individual bars equipped with tape-supporting lugs may be applied to the carrier-chains at suitable intervals to support the tapes. The cross-bars of the carrier may be connected at their ends with the links of the carrier-chains in any suitable manner. As may be understood from Fig. 3, the shoes 47 which serve as mountings for the gripper devices are connected with the chains by extending two of the link pivots 72 and riveting them to the shoes. Associated with the sheet-receiving platforms G and G' are jogging-devices H and H' which serve to properly stack the sheets of paper as they drop upon the platform. These devices are of the same construction and will be understood from Figs. 1 and 17 to 20, inclusive, which show the device H'. This device comprises a pair of cross-bars or shafts 73 which are rigidly supported by the frame A; a pair of longitudinal bars 74 adjustably mounted on

the supporting bars 73 and capable of being adjusted toward and away from each other; a pair of cross-bars 75 adjustably connected with the longitudinal bars 74 by means of clips 76, thus forming a rectangular frame through which the sheets may fall, this frame being capable of adjustment to accommodate sheets of different sizes; adjustable clips or blocks 77 mounted on the bars of said frame; reciprocable jogging-members 78 provided with shanks 78^a which extend through suitable guides in the blocks 77; bell-crank levers 79 mounted on pivots 80 carried by the blocks 77, the levers 79 being connected by links 81 with the shanks 78^a; and a system of actuating rods 82 connected with and serving to oscillate the bell-crank levers and thus reciprocate the jogging-members 78, one of the rods 82 being actuated by a bell-crank lever 83, which, in turn, is actuated by a cross-rod 84.

The rod 84 is reciprocated by means of the following mechanism: The shaft of the cylinder 38 is equipped with a pinion 85 which actuates a gear 86 with which is connected a pitman-rod 87 which serves to oscillate a bell-crank lever 88. The bell-crank lever 88 works in a vertical plane and serves to actuate a link 89 which actuates a bell-crank lever 90 which works in a horizontal plane. The rod 84 is extended past the side frame of the machine and connected with the bell-crank lever 90, and thus the system of rods 82 is actuated through the medium of the rod 84.

The platform-support G' is supported by chains 91 which are paid out by mechanism of a well-known type, which includes a ratchet device 92 and a connecting-rod 93 which is actuated by the bell-crank lever 88. The connecting-rod 93 is connected directly with an oscillating-arm which carries a friction-pawl 94. The connection between said arm and the link 93 is adjustable, as indicated at 95, so that the movement may be very finely regulated, thus enabling the platform G' to be lowered just the thickness of a sheet of paper at each operation of the pawl.

The mechanism for automatically lowering the frame G is of the same character and is designated generally by the reference character 96.

It should be stated, with reference to Fig. 17, that the joggers 78, alternately, reciprocate in opposite directions. This is accomplished by properly locating the bell-crank levers 79 with reference to their points of pivotal support 80. It may be stated, also, that at one side of the frame, one of the bars 75 is equipped with fixed vertical guides 75^a which serve to engage the lateral edges of the sheets as they are dropped upon the support G'.

The operation of the machine may be stated briefly. The printing mechanism has the tympan cylinder B provided with a plurality of impression surfaces (in this case two), the press thus being adapted to produce a printed sheet from each impression surface; and the delivery mechanism is provided with a plurality of endless conveyors (in this case two), each adapted to receive the printed sheets from a particular impression surface of the tympan cylinder. All of the sheets from the tympan cylinder are carried by the transfer cylinder D to the distributing cylinder E. The grippers of the cylinder E are adapted to be opened at different points by means of the shiftable cams 22 and 23, which cause the sheets to be released at the proper points to enable them to be taken up, in alternation, by the grippers of the upper endless conveyor and by the grippers of the lower endless conveyor. Each endless conveyor is equipped at proper intervals with gripper devices so disposed and timed that a gripper will be presented at the proper instant to receive a sheet from the distributing cylinder E. The printed surfaces of the sheets are outwardly turned on the impression cylinder B, are inwardly turned on the transfer cylinder D, are outwardly turned on the distributing cylinder E, and are turned downwardly on the upper sides of the endless conveyors. The sheets are carried rearwardly by the upper sides of the endless conveyors and then carried around under the discharge ends of said conveyors and dropped upon the platforms G and G'. The speed of operation is such that the sheets require no support other than their engagement by the grippers during the short interval when they are moving across the platforms G and G', preparatory to being dropped upon said platforms. At the proper instants, the grippers are released by the cams 58 and 59, thus permitting the sheets to drop. The system of joggers shown in Figs. 17 to 20, inclusive, operates to properly stack the sheets as they drop upon the platforms. The movement of the joggers is effected by the mechanism 85 to 90, inclusive, and the platforms G and G' are automatically lowered the thickness of a sheet at each operation by means of the mechanism 93-94, in one case, and the mechanism 96, in the other case.

The delivery mechanism is capable of operating at sufficiently high speed to take care of the output of the press. This is accomplished by the employment of a plurality of endless conveyors and suitable distributing means for delivering the sheets to said conveyors. The operation is such as to afford the ink some time to dry during the period of transfer from the tympan cylinder to the stacks of sheets; and, when the

sheets are deposited on the stacks, it is with the printed side up. It will be understood by those skilled in the art that, if desired, slip-sheets may be fed to the tympan cylinder in such manner as to supply slip-sheets between the printed sheets when they are stacked on the platforms G and G'.

The improved delivery mechanism enables a rotary press of the character described to be operated to its full capacity, the delivery mechanism being capable of handling the output without injury to the product.

Each of the endless conveyors may be equipped with a suitable number of gripper devices. For example, the lower conveyor may be equipped with two separate gripper devices, or with four separate gripper devices, while the upper conveyor may be equipped with seven separate gripper devices, the gripper devices of each conveyor being suitably spaced to adapt it to accommodate the sheets which are to be carried. The total length of each chain of each conveyor should constitute a multiple of the circumference of the tympan cylinder as well as of the distributing cylinder. In the illustration given, the lower conveyor is shown equipped with two separate gripper devices, but as indicated this conveyor is of such length that it may, if desired, be equipped with four sets of gripper devices. On the other hand, the upper conveyor is of such length as to enable it to be equipped with seven sets of gripper devices, and may be assumed to be so equipped.

Reverting to the fact that the shiftable cams 22 and 23 operate alternately to trip the gripper device of the distributing cylinder at different points, so as to effect alternate delivery of the sheets to the two endless conveyors, it is obvious that by disconnecting the cam wheel 30, shown in Fig. 13, the cam 22 may remain fixed in the position shown in Fig. 18, under which condition the gripper device of the distributing cylinder would always trip at a point to deliver the sheets to the upper conveyor. Thus, if desired for any reason, all of the sheets might be delivered in one pile by the upper conveyor. In a similar manner, the cam device might be so set that the cam 23 would operate always to trip the gripper device of the distributing cylinder, so that all of the sheets would be delivered to the lower conveyor; and assuming the lower conveyor to be equipped with the requisite number of gripper devices, all of the sheets might then be delivered in one pile through the medium of the lower conveyor.

With the machine set to effect delivery from the distributing cylinder to the upper endless conveyor only, for example, it is possible with a press of the character described in the above mentioned patent to print two-

color work on a sheet passing through a printing press and to follow each printed sheet with a slip-sheet, the printing cylinders failing to print on the slip-sheet. In this manner slip-sheets may be interposed between the printed sheets. This may be a desirable method of operation, especially where heavy solids are being employed.

The foregoing detailed description has been given for clearness of understanding only, and no unnecessary limitation should be understood therefrom, but the appended claims should be construed as broadly as permissible in view of the prior art.

What I regard as new, and desire to secure by Letters Patent, is—

1. In mechanism of the character set forth, the combination with a plurality of endless conveyors of different lengths, each conveyor being equipped with gripper devices and having its upper side travelling rearwardly and carrying the sheets rearwardly thereon, of means for feeding sheets of paper automatically to said conveyors in alternation, and means for tripping the gripper devices after the sheets have been carried to the under sides of the conveyors.

2. In mechanism of the character set forth, the combination of a pair of endless conveyors equipped with gripper devices, a distributing cylinder equipped with a gripper device, and a cam device adapted to effect release of the gripper device of said distributing cylinder at different points, corresponding with the points at which the gripper devices of the endless conveyors operate to grip the sheets.

3. In mechanism of the character set forth, the combination of a pair of endless conveyors of different lengths, sheet-stacking devices beneath the discharge end portions of said conveyors, a distributing cylinder at the front ends of said conveyors, said cylinder being equipped with a gripper device, and means for effecting release of the gripper device of said cylinder at the front end of one of said conveyors and at the front end of the other of said conveyors automatically, in alternation.

4. In mechanism of the character set forth, an endless conveyor comprising cylinders, endless chains associated therewith, a gripper device comprising mountings carried by said chains, one of said mountings being in the form of a shoe, a cross-shaft connecting said mountings, a rock-shaft carried by said mountings, grippers carried by said rock-shaft, an arm adapted to actuate said rock-shaft, guides adapted to engage said shoe in its course about said cylinder at the front end of the conveyor, and a cam adapted to actuate said arm to trip the gripper device in its passage about said cylinder.

5. In mechanism of the character set forth, an endless conveyor comprising cylin-

- ders, endless chains associated therewith, a gripper device mounted on said chains and equipped with a shoe and with a trip-arm, a concave guide concentric with the cylinder at the front end of the conveyor within which said shoe is adapted to travel in close-confining contact, and a trip-cam adapted to actuate said arm during the passage of said shoe through said concave guide.
10. 6. In mechanism of the character set forth, an endless conveyor comprising cylinders, endless chains associated therewith, a gripper device mounted on said chains and equipped with a shoe and with a trip-arm, a concave guide concentric with the cylinder at the front end of the conveyor within which said shoe is adapted to travel, means carried with said last-named cylinder and opposed to said concave guide for engaging the opposite edge of said shoe during its passage about the axis of said cylinder, and a trip-cam adapted to actuate said arm during the passage of said shoe through said concave guide.
15. 7. In mechanism of the character set forth, an endless conveyor equipped with a gripper device provided with a shoe and with a trip-arm, means for guiding and confining said shoe in its passage about the axis of the cylinder at the front end of said conveyor, and means for tripping said arm while said shoe is confined by said guiding means.
20. 8. In mechanism of the character set forth, the combination of suitable side frames, cylinders journaled therein, sprocket-wheels associated with said cylinders, sprocket-chains mounted on said sprocket-wheels, a gripper device mounted on said sprocket-chains and provided with a shoe and with a trip-arm, a bracket carried by one of said side frames, means for guiding and confining said shoe during its passage about the axis of the cylinder at the front end of said conveyor, and a cam connected with said bracket and serving to trip said arm during the movement of said shoe about said axis.
25. 9. In mechanism of the character set forth, the combination of an endless conveyor comprising chains, a gripper device mounted on said chains and equipped with a trip-arm, a cam adapted to actuate said trip-arm, and means for preventing displacement of the gripper device during the actuation of said trip-arm.
30. 10. In mechanism of the character set forth, the combination of cylinders, sprocket-wheels associated with said cylinders, sprocket-chains mounted on said sprocket-wheels, guides for said sprocket-chains, a gripper device comprising mountings carried by said sprocket-chains, one of said mountings affording a shoe, a shaft con-
- necting said mountings, a rock-shaft carried by said mountings, grippers carried by said rock-shaft, a spring connected with said rock-shaft and serving to close said grippers, a trip-arm connected with said rock-shaft, a cam adapted to actuate said trip-arm, and a guide adapted to engage said shoe and prevent displacement of the gripper device during the actuation of said trip-arm.
35. 11. In mechanism of the character set forth, the combination of a pair of side frames, an upper pair of cylinders journaled in said side frames, a lower pair of cylinders journaled in said side frames, endless conveyors mounted on said cylinders, brackets carried by said side frames, guide-members carried by said brackets and serving to support the chains of said endless conveyors, gripper devices carried by the chains of said conveyors, said gripper devices being equipped with trip-arms, and trip-cams connected with said brackets and adapted to actuate said trip-arms.
40. 12. In mechanism of the character set forth, the combination of an endless conveyor comprising cylinders, sprocket-chains associated therewith, cross-bars mounted in a group on said chains, a gripper device mounted on said chains, and longitudinal tapes mounted on said cross-bars.
45. 13. In mechanism of the character set forth, an endless conveyor comprising cylinders and sprocket-wheels associated therewith, said cylinder having segmental recesses, sprocket-chains mounted on said sprocket-wheels, a gripper device mounted on said sprocket-chains and adapted to enter said segmental recesses, cross-bars mounted in a group on said chains and equipped with bearing lugs, and longitudinal tapes secured to one cross-bar and supported by the lugs of the other cross-bars, said cross-bars being adapted to enter as a group in the cylinder-recesses.
50. 14. In mechanism of the character set forth, an endless conveyor comprising cylinders provided with segmental recesses, sprocket-wheels associated with said cylinders, sprocket-chains mounted on said sprocket-wheels, a gripper device mounted on said sprocket-chains, a group of cross-shafts mounted on said sprocket-chains and adapted to enter a segmental recess in a group, and longitudinal tapes supported by said cross-shafts.
55. 15. In mechanism of the character set forth, the combination with endless chains of an endless conveyor, of a gripper device mounted on said chains, a cross-shaft mounted on said chains and equipped with a plurality of tape-securing clips, longitudinal tapes secured to said clips, and other cross-shafts mounted on said chains and provided

- with bearing-lugs adapted to support said tapes.
16. In mechanism of the character set forth, the combination of a pair of endless conveyors equipped with gripper devices, a distributing cylinder disposed adjacent the front ends of said conveyors and equipped with a gripper device of said cylinder to admit a sheet, and automatic means for opening the gripper device of said cylinder at the front end of one of the endless conveyors and then at the front end of the other endless conveyor, in alternation.
17. In mechanism of the character set forth, the combination of a pair of endless conveyors equipped with gripper devices, a distributing cylinder disposed adjacent the front ends of said conveyors and equipped with a gripper device, means for opening the gripper device of said cylinder to admit a sheet, a pair of shiftable cams, one of which is adapted to trip the gripper device of said cylinder at the front end of one of said conveyors and the other of which is adapted to trip said gripper device at the front end of the other of said conveyors, and means for shifting said cams at each revolution of said cylinder.
18. In mechanism of the character set forth, the combination of a pair of endless conveyors equipped with gripper devices, a distributing cylinder equipped with a gripper device of said cylinder to admit a sheet, and a cam device for opening the gripper device of said cylinder at the front ends of said conveyors alternately, comprising a pair of shiftable cams, a reciprocating cross-head connected therewith, and a cam-wheel serving to actuate said cross-head, said cam-wheel being timed to shift said cross-head in one direction or the other at each rotation of said cylinder.
19. In mechanism of the character set forth, the combination with the printing mechanism of a press, of delivery mechanism comprising a pair of endless conveyors having their upper sides traveling towards their discharge ends, means for delivering sheets of paper to said conveyors so that they will be carried rearwardly by the upper sides of the conveyors, and means for effecting discharge of the sheets from the conveyors during the return trips of the sheets at the lower sides of the conveyors.
20. In mechanism of the character set forth, the combination with the printing mechanism of a press, of a pair of endless conveyors, a distributing cylinder adapted to deliver sheets to the front ends of the conveyors, and a transfer cylinder interposed between the distributing cylinder and the printing mechanism and serving to deliver sheets to the distributing cylinder.
21. In mechanism of the character set forth, the combination with a tympan cylinder provided with two impression surfaces and two sets of grippers, of a distributing cylinder provided with one set of grippers and adapted to receive sheets from the tympan cylinder, a pair of endless conveyors having their front ends associated with the distributing cylinder, said conveyors being provided with grippers, and means for automatically opening the grippers of said distributing cylinder at different points to enable alternate sheets to be delivered from the distributing cylinder to each conveyor.
22. In mechanism of the character set forth, the combination with printing mechanism having a tympan cylinder provided with a plurality of impression surfaces, of a plurality of endless conveyors corresponding in number with the number of impression surfaces of said tympan cylinder, and means interposed between the tympan cylinder and the front ends of said conveyors, whereby sheets may be delivered from the tympan cylinder to the several conveyors.
23. In mechanism of the character set forth, the combination with printing mechanism having a tympan cylinder provided with a plurality of impression surfaces, of a plurality of endless conveyors corresponding in number with the number of impression surfaces of said tympan cylinder, and sheet-distributing means interposed between the tympan cylinder and said endless conveyors, adapted to deliver the sheets from a given impression surface of the tympan cylinder to a given one of said endless conveyors.
24. In mechanism of the character set forth, the combination with printing mechanism, of a plurality of endless conveyors, and distributing means interposed between the printing mechanism and said endless conveyors adapted to be set to deliver sheets consecutively to one conveyor or alternately to the several conveyors, as desired.
25. In mechanism of the character set forth, the combination with printing mechanism having a tympan cylinder provided with a plurality of impression surfaces, of a plurality of endless conveyors corresponding in number with the number of impression surfaces of said tympan cylinder, and sheet-distributing means interposed between said tympan cylinder and the front ends of said conveyors and adapted to be set to deliver sheets consecutively to one of said conveyors or alternately to the several conveyors, as desired.

WALLACE S. WARNOCK.
